UNITED STATES PATENT OFFICE.

JOHN MARKMANN, OF MUSCATINE, IOWA, ASSIGNOR OF ONE-HALF TO
PHILIP J. MACKEY, OF SAME PLACE.

SHAPE-RETAINER FOR THE BREASTS OF GARMENTS.

SPECIFICATION forming part of Letters Patent No. 357,397, dated February 8, 1887.

Application filed July 12, 1886. Serial No. 207,812. (No model.)

To all whom it may concern:

Be it known that I, JOHN MARKMANN, a citizen of the United States of America, residing at Muscatine, in the county of Muscatine and State of Iowa, have invented certain new and useful Improvements in Garment - Breast-Shape Retainers, of which the following is a specification, reference being had therein to the accompanying drawings.

10. My invention relates to devices for retaining in shape the breasts of garments; and it consists of a bifurcated plate of spring-brass, or any other suitably firm and elastic material, the two parts of the plate being provided with 15 perforations to admit of being stitched to the garment and shaped to conform to the shape of the breast of the garment to which it may be attached, as hereinafter fully set forth and claimed.
20. In the accompanying drawings, Figure 1 is a perspective view of the breast-shape retainer detached. Fig. 2 is a view of the retainer-plate covered with cloth. Fig. 3 is a view with lining and facing of the breast of a garment removed, showing the shape-retainer attached in position to the garment. Fig. 4 is an outside view of the breast of a garment having the shape-retainer attached and its position shown in dotted lines.
25. A A' designate the two parts of the shape-retainer, of any required length, united together at *a*, at any required angle, so that the part A may be placed parallel with the front line, *b*, and the part A' will extend in the required direction across the breast of the garment, as shown in the drawings.
30. The part A is curved along its front edge and on its side to enable it to conform to and hold the breast of a garment in the required

shape along its front line, and the part A' is 40 curved on its side to conform to and hold a garment in shape across its breast. The retainer is fastened to the breast of a garment between the lining or facing and the outer cloth by stitching through the perforations *c* 45 near the edges of the plates, as shown.

The plates are covered with any suitable fabric, *d*, before the retainer is attached to the garment. The plates, being made as thin as practicable of spring-brass or some other material that possesses the requisite elasticity and firmness, will add no appreciable weight to but will cause the breasts of the garment to retain the smooth unbroken shape of the body of the person wearing the garment. 50

These retainers, it is evident, are easily made and are inexpensive, and not being liable to be broken or worn out, may, when it is desirable, be removed from worn-out garments and attached to new garments, saving 60 the expense of new stiffenings or retainers. 55

What I claim as new, and desire to secure by Letters Patent, is—

The combination, with the breast of a garment, of the bifurcated shape-retainer consisting of the curved perforated parts A A', the part A being adapted to conform to and hold a garment in the required shape along its front line and the part A' being adapted to conform to and hold a garment in the required shape across its breast, substantially as and for the purposes described. 65

In testimony whereof I affix my signature in presence of two witnesses.

JOHN MARKMANN.
